(57) CLAIM

The ornamental design for a head for a handheld beauty care device, as shown and described.

DESCRIPTION

FIG. 1 is a top plan view of a head for a handheld beauty care device;

FIG. 2 is a first-side elevational view thereof;

FIG. 3 is a second-side elevational view thereof;

FIG. 4 is a bottom plan view thereof;

FIG. 5 is a third-side elevational view thereof;

FIG. 6 is a fourth-side elevational view thereof; and,

FIG. 7 is a perspective view thereof from the side and bottom.

The broken lines depict portions of the head for a handheld beauty care device that form no part of the claimed design.
